(57) **CLAIM**

The ornamental design for a case for a collectible postage stamp, as shown and described.

DESCRIPTION

FIG. 1 is a perspective view of a case for a collectible postage stamp in accordance with a first embodiment.

FIG. 2 is an elevation view of a back side of the case for a collectible postage stamp in accordance with the first embodiment.

FIG. 3 is an elevation view of the front side of the case for a collectible postage stamp in accordance with the first embodiment.

FIG. 4 is an elevation view of a right side of the case for a collectible postage stamp in accordance with the first embodiment.

FIG. 5 is an elevation view of a left side of the case for a collectible postage stamp in accordance with the first embodiment.

FIG. 6 is a plan view of the top side of the case for a collectible postage stamp in accordance with the first embodiment.

FIG. 7 is a plan view of the bottom side of the case for a collectible postage stamp in accordance with the first embodiment.

FIG. 8 is a perspective exploded view of the case for a collectible postage stamp in accordance with the first embodiment.

FIG. 9 is a cutaway elevation view of the case for a collectible postage stamp along the sight lines indicated in FIG. 2 in accordance with the first embodiment.

FIG. 10 is an close up view of a side of the case for a collectible postage stamp as indicated in FIG. 4 in accordance with the first embodiment.

FIG. 11 is a perspective view of a case for a collectible postage stamp in accordance with a second embodiment.

FIG. 12 is an elevation view of a back side of the case for a collectible postage stamp in accordance with the second embodiment.

(Continued)

FIG. 13 is an elevation view of the front side of the case for a collectible postage stamp in accordance with the second embodiment.

FIG. 14 is an elevation view of a right side of the case for a collectible postage stamp in accordance with the second embodiment.

FIG. 15 is an elevation view of a left side of the case for a collectible postage stamp in accordance with the second embodiment.

FIG. 16 is a plan view of the top side of the case for a collectible postage stamp in accordance with the second embodiment.

FIG. 17 is a plan view of the bottom side of the case for a collectible postage stamp in accordance with the second embodiment.

FIG. 18 is a perspective exploded view of the case for a collectible postage stamp in accordance with the second embodiment.

FIG. 19 is a cutaway elevation view of the case for a collectible postage stamp along the sight lines indicated in FIG. 12 in accordance with the second embodiment.

FIG. 20 is a close up view of a side of the case for a collectible postage stamp as indicated in FIG. 14 in accordance with the second embodiment.

FIG. 21 is a perspective view of a case for a collectible postage stamp in accordance with a third embodiment.

FIG. 22 is an elevation view of a back side of the case for a collectible postage stamp in accordance with the third embodiment.

FIG. 23 is an elevation view of the front side of the case for a collectible postage stamp in accordance with the third embodiment.

FIG. 24 is an elevation view of a right side of the case for a collectible postage stamp in accordance with the third embodiment.

FIG. 25 is an elevation view of a left side of the case for a collectible postage stamp in accordance with the third embodiment.

FIG. 26 is a plan view of the top side of the case for a collectible postage stamp in accordance with the third embodiment.

FIG. 27 is a plan view of the bottom side of the case for a collectible postage stamp in accordance with the third embodiment.

FIG. 28 is a perspective exploded view of the case for a collectible postage stamp in accordance with the third embodiment.

FIG. 29 is a cutaway elevation view of the case for a collectible postage stamp along the sight lines indicated in FIG. 22 in accordance with the third embodiment.

FIG. 30 is a close up view of a side of the case for a collectible postage stamp as indicated in FIG. 24 in accordance with the third embodiment.

FIG. 31 is a perspective view of a case for a collectible postage stamp in accordance with a first embodiment, but showing a disclaimed certification label and a disclaimed postage stamp for context; and,

FIG. 32 is an elevation view of a front side of the case for a collectible postage stamp in accordance with the first embodiment, but showing a disclaimed certification label and a disclaimed postage stamp for context.

In the drawings, the broken lines showing a certification label and a postage stamp represent environmental subject matter that forms no part of the claimed design.
